UNITED STATES PATENT OFFICE.

JAMES E. JAGGER, OF HOLYOKE, MASSACHUSETTS, ASSIGNOR TO HOLYOKE PLUSH COMPANY, OF HOLYOKE, MASSACHUSETTS, A CORPORATION OF MAINE.

DESIGN FOR A WOVEN FABRIC.

51,417.

Specification for Design.

Patented Oct. 23, 1917.

Application filed January 13, 1917. Serial No. 142,328. Term of patent 7 years.

To all whom it may concern:

Be it known that I, JAMES E. JAGGER, a citizen of the United States, residing at Holyoke, county of Hampden, State of Massachusetts, have invented a new, original, and ornamental Design for a Woven Fabric, of which the following is a specification, reference being had to the accompanying drawing, forming a part hereof.

The figure is a plan view of a section of woven fabric showing my new design.

The portions shown in dark color are depressed and the portions shown light are elevated.

The effect is produced in the pile fabric by embossing the portions shown as dark colored so as to bring them beneath the general surface of the body of the fabric.

I claim:

The ornamental design for a woven fabric as shown and described.

JAMES E. JAGGER.
